UNITED STATES PATENT OFFICE.

FERDINAND J. TILLMAN, OF ST. LOUIS, MISSOURI.

ADDING-MACHINE.

1,120,347.

Specification of Letters Patent.

Patented Dec. 8, 1914.

Application filed February 24, 1913. Serial No. 750,092.

To all whom it may concern:

Be it known that I, FERDINAND J. TILLMAN, a citizen of the United States of America, residing in the city of St. Louis and State of Missouri, have invented certain new and useful Improvements in Adding-Machines, of which the following is a specification.

The primary object of this invention is to 10 provide an improved calculating machine that is small, simple, and inexpensive, and can easily be carried.

Another object is to provide an adding machine of this character in which the 15 entire operation can be readily done with one hand of the operator.

A further object is to provide improved means whereby, after one number has been selected, the means for recording such number 20 is always adjacent the hand of the operator so that the hand will not have to be carried over to any other part of the adding machine.

A still further object is to provide means 25 whereby the sum, or total, after being selected, is held in a row for inspection until recorded.

Other and further objects will appear in the specification, and be specifically pointed 30 out in the appended claims, reference being had to the accompanying drawings exemplifying the invention, and in which,

Figure 1 is a longitudinal section through this adding machine. Fig. 2 is a fragmentary plan view, partly in section, taken on the line II-II, Fig. 1. Fig. 3 is a transverse vertical section taken on the line III-III, Fig. 1. Fig. 4 is a vertical section of a portion of this improved adding machine, 35 taken on the line IV-IV, Fig. 1. Fig. 5 is a section on the line V-V, Fig. 3. Fig. 6 is a section taken on the line VI-VI, Fig. 5. Fig. 7 is a fragmentary plan view, parts being shown in section, taken on the line 40 VII-VII, Fig. 1. Fig. 8 is a fragmentary perspective view, partly in section, showing a portion of the stop bar and its attachments. Fig. 9 is a portion of a longitudinal section of this improved adding machine, similar to 45 Fig. 1, some of the parts being shown in shifted position.

Referring to the drawings: 1 designates a casing which is mounted on the feet 2, said casing having the side walls 3, front wall 4, and end wall 5. It is to be noted 50 that the front wall 4 does not extend down-

wardly the full depth of the casing, there being another front wall 6 formed on said casing at a distance in from the front wall 4. Between the said front walls 4 and 6, and 60 adjacent their lower and upper ends, respectively, is formed an opening 7. The casing 1 also has a top wall 8, and a bottom wall 9.

Formed in the top wall 8, adjacent the 65 center thereof, is a rectangular opening 10. Formed on the front wall 4 and end wall 5, on the inside and adjacent the top thereof, are a series of supporting sockets 11, said sockets being in longitudinal alinement with 70 each other, and adapted to secure a series of trackways 12 thereto. Mounted on said trackways 12 are a series of selector bars 13, said selector bars being normally held toward the rear of the casing by helical 75 springs 14. Said springs are secured at one end to the end wall 5, as shown at 15, and are secured to the selector bars on their under side by the screw eyes 16. Said selector bars abut at their rear ends against a 80 cushioning strip 17, which cushioning strip is mounted over the trackways 12 adjacent the supporting sockets 11 of the end wall 5.

Formed on the under side of each selector bar is a series of rack teeth 18, which series 85 of rack teeth are adapted to engage with the pinion 19. Said pinions are mounted on a horizontal shaft 20. Formed integral with each pinion 19, and on one side thereof, is a hub 21, said hub having outstanding arms 90 22 on which is mounted the spring actuated pawl 23. Said pawl is adapted to engage the teeth of the ratchet wheel 24, which ratchet wheel is secured to the transmission gear 25.

Mounted between each of the pinions 19 and transmission gears 25, on the shaft 20, are spacer sleeves 26. Meshing with each transmission gear 25 are gears 27, each of said gears 27 being secured to the totalizing wheel 28. Formed on one side of each totalizing wheel is a hub 29. Formed on each hub 29 is an intermittent wheel 29. All of said parts 27, 28, 29 and 30 are loosely mounted on the horizontal shaft 31. Said 100 shaft is journaled in the bearings 32 formed on the side walls 3.

Depending downwardly from the rear ends of each of the selector bars 13 is an extension 33. Pivottally mounted to each of 110 said extensions, at one end, as shown at 34, is a combined stop and numeral bar 35, each

of said bars 35 being supported at its opposite end by a spring 36. Said springs are supported from the forward end of the selector bars 13.

5 Extending transversely across the top of the adding machine, adjacent the forward end of the rectangular opening 10, is a recording bar 37. Said recording bar has a depending portion 38 on each side. Each 10 of said depending portions extends downwardly to a point below the selector bars, and then converges into a horizontal portion 39. Said horizontal portion, at its end, is pivoted to the side walls by pivots 40. 15 Connecting said horizontal portions 39, and extending transversely across the casing 1, is a combined retaining and striking bar 41. In order to hold the recording bar 37 in an inactive position a pair of springs 42 are 20 used, each of said springs connecting with each depending portion 38, and being secured to the under side of the top wall 8 by screw eyes 43.

Located adjacent the forward end of the 25 rectangular opening 10, and also adjacent the recording bar 37, is a stop bar 44. Said stop bar is adapted to extend the full width of the rectangular opening 10, and has depending portions 45 adjacent its ends. Said 30 depending portions are pivoted adjacent their centers at 46 to the side walls 3. The lower ends of said portions 45 are pivoted at 47 to the side portions 48 of an engaging bar 49. Said side portions 48 are slidably 35 mounted in guides 50.

Located under and adjacent the forward end of the stop and numeral bar 35 is an inking roller 51 which is revolubly mounted on the shaft 52, and swingingly mounted 40 to the side walls 3 by supporting bars 53. Said supporting bars 53 are pivoted at one end to said side walls, as shown at 54. Springs, such as 55, are secured to said supporting bars 53 to hold said inking roller 45 51 in engagement with the numeral blocks 56 which are formed on the under side of the bars 35. Formed on the upper side of each of said bars 35 are a series of engaging members 57, said members being disposed on said bars opposite to the numeral blocks 56.

55 Formed adjacent the inking roller 51, and extending across the casing 1 parallel with said inking roller is a feed roll 58 which is mounted on the shaft 59, said shaft being supported by the side walls 3. Mounted on said feed roll, at each end, is a ratchet wheel 60. The ratchet wheels are adapted to be engaged by spring actuated pawls 61. 60 Said pawls are carried by the horizontal portions 39 of the recording bar 37.

65 Extending transversely across the casing 1, parallel with and adjacent the numeral wheels 28, is a striking bar 62. Said striking bar is swingingly mounted on the shaft

63, which is supported in the side walls 3, and is held in an inoperative position by springs 64. Said springs normally hold the said striking bar against stops 65. Formed adjacent the center of said striking bar is an 70 outstanding lug 66. Said lug is adapted to be operated upon by a striking lever 67, which is securely mounted on the shaft 68. Said shaft, at one end, extends outside of one of the side walls 3, and has mounted 75 thereon a lever 69.

Mounted upon a transverse shaft 70, adjacent the center of the casing 1, is a roll of paper 71, which is adapted to be printed upon during the operation of the machine. 80 The paper passes under guide rollers 72, one of said guide rollers being mounted on the shaft 63 of the striking bar 62. Continuing, the paper passes between a roller 73, which is carried by said striking bar, 85 and the pressure member proper of said bar, and continuing on passes under another roller 74 and around the upper periphery of the feed roller 58, then under a roller 75 out to the front of the machine adjacent the 90 opening 7.

Extending across the casing 1, on the under side of the bars 35, and adjacent the paper roll 71, is a supporting bar 76, which is secured to the side walls 3. Extending 95 from said bar are a series of pins 77 on which are mounted a series of spring actuated pawls 78. The retaining portions 79 of said pawls are adapted to engage against one side of each bar 35. Formed on top of 100 each bar 35, adjacent the point of engagement, of the retaining portion 79 of the pawl 78 are inclined cutaway portions 80, which is more clearly shown in Figs. 2 and 4. Located adjacent the under side of the 105 totalizing wheels 28, and bearing against said wheels, is an inking roller 81.

In the operation of this improved adding machine, assume that the first number of a column of figures to be added is "345." Said 110 number is selected on the first three selector bars to the right. As the fingers of the hand are directed to one or all of the selected numbers, each finger will engage one of the 115 projections 82. There are a series of these projections on each of the selector bars 13. The selector bars are drawn toward the front of the machine until the fingers of the operator engage against the stop bar 44. As 120 each selector bar 13 is moved, the teeth 18 formed on the under side thereof will engage a pinion 19. By reason of each pinion 19 having a hub portion 21, the pawl 23 that is carried by said hub portion will engage the ratchet wheel 24, which ratchet wheel 125 will then carry the transmission wheel 25. Said transmission wheel 25 will then rotate the totalizing wheel 28 through the gear 27. It is to be noted that when each selector bar is moved it carries with it the combined stop 130

and numeral bar 35. In the instance of carrying the selected numeral "3" said numeral will be drawn toward the front of the machine until stopped by the operator's finger engaging the stop bar 44. One of the engaging members 57 formed on the bar 35, which engaging member is designated as 83, will be engaged against the striking bar 41, which will hold the selector bar in position until after recording. It is to be noted that the number of engaging members 57 is equal to the number of numeral blocks 56, as well as the engaging members 82. So that whatever number is selected on any selector bar, said selector bar is moved forward to its limit of movement. One of the engaging members 57 will hold the selector bar in its moved position by its engagement with the striking bar 41. Whenever a number has been selected on the selector bar, and the selector bar has been moved, one of the numeral blocks 56, bearing a number corresponding with the number selected, will be carried forward by the bar 35 and will remain in the recording position over the roller 58. After the selector bars, bearing the selected numbers "3," "4," "5," have been moved forward and are held in position for recording by the operation just described, the recording bar 37 has a pressure brought to bear upon it, and the striking bar 41 will be carried downwardly, bearing down the bar 35. The numeral blocks 56, carrying the numerals "3," "4," "5," will bear against the paper sheet, which paper sheet is engaged over the upper periphery of the roll 58, and the numerals "3," "4," "5," will be printed thereupon. When the pressure is relieved from the recording bar 37, the springs 42 will return said recording bar to its normal position, and the spring actuated pawls 61, which are carried by said recording bar, will engage the ratchet wheels 60. This will then turn the paper sheet on which the numbers have been recorded a space so as to be ready for the next elected number. At the time the striking bar 41 depressed the bars 35, said bars were depressed to such an extent that the top portion thereof was engaged by a portion of their respective spring actuated pawls 78. As the striking bar 41 was returned to its normal position, the bars 35 of the three selected numbers were held down so that the engaging portions 57 of said bars could pass under the striking bar 41, as said bars 35 and the selector bars 13 are returned to their normal position by the springs 14. At this point the cutaway portions 80 formed on the upper portion of the bars 35 will be in alignment with the spring actuated pawls 78 so that the retaining portion 79 of said pawls will slide off from said bars 35 upon their engagement with said cutaway portions 80.

In order to understand the operation of the returning of the selector bar 13 and bars 35 to their normal position, an inspection of Fig. 9 shows one of the pawls 78 engaging the top of one of the bars 35, thus holding the engaging members 57 out of engagement with the striking bar 41. As the selector bars 38 are drawn forward in the order in which the numbers thereon are elected and engaged by the operator's fingers, the fingers, upon engaging the stop bar 44, will move said stop bar, thus carrying the engaging bar 49 into engagement with the teeth of the transmission wheels 25. This is merely to stop the momentum from carrying the transmission wheels beyond their intended distance. Each of the transmission wheels 25 has mounted thereon a projection 84, which projection, upon continued operation of the selector bars in the order of adding, will engage with its respective intermittent wheel 30 so as to carry the numeral wheel 28 to the next order. After a column of figures has been brought down and recorded by the actuation of the selector bars 13, and the recording bar 37, and the total is desired, the lever 69 is pressed down which will cause the striking lever 67 to be engaged against the lug 66 of the striking bar 62, which will cause the striking bar 62 to be engaged against the proper totaling numerals on the totaling wheel. As the sheet of paper will be between said striking bar and the totaling numerals to be recorded, the total will be printed on said sheet. After the pressure has been removed from the lever 69, the actuating parts relating to said striking bar 62 will be returned to their normal positions. The sheet of paper can then be engaged through the opening 7 of the casing 1, and the sheet of paper drawn forward, and a portion of the paper sheet containing the recorded figures, can then be torn off in any suitable manner.

In the drawing forward of the selector bars 13, it is to be noted that when the operator's fingers are adjacent the stop bar 44, the rear portion of the operator's hand will be above the recording bar 37. So that by a mere downward movement of the heel of the hand said recording bar will be depressed, whereupon the elected numbers will be recorded, and the operating parts returned to their normal positions. Therefore, it is not necessary for the operator to move his hand to any other part of the machine. For this reason, the operation of this improved adding machine can be carried on very rapidly, which is done solely by the drawing down of the finger and the rapid movement of the downward depression of the rear portion of the palm of the hand. Attention is called to the fact that when any numbers have been selected and drawn down by the manipulation of the

lector bars, said numbers will be in a straight line and so held that said numbers can be checked or inspected. Also, the mere drawing forward of said selector bars activated all the operative parts so that everything is in position for recording when said selector bars have been drawn down to their limit of movement, which limit is governed by the operator's fingers engaging the stop bar 44.

10 What I claim is:

1. In an adding machine, a sliding selector bar therefor adapted to be operated to different extents, said selector bar having a stop bar pivotally mounted thereto.

2. In an adding machine, a sliding selector bar therefor adapted to be operated to different extents, a totalizer wheel operated by said selector bar, a combined stop and numeral bar pivotally mounted to said selector bar, said stop bar adapted to hold said selector bar in a selected position.

3. In an adding machine, a sliding selector bar therefor adapted to be operated to different extents, a totalizer wheel operated by said selector bar, a stop bar pivotally mounted to said selector bar, numerals carried by said stop bar, means located adjacent said stop bar for holding the numerals thereon in a position for recording, and means for depressing said stop bar whereby said selector bar can be returned to its normal position.

4. In an adding machine, a selector bar, a numeral bar carried by said selector bar, means for swinging said numeral bar downwardly from said selector bar, said numeral bar adapted to release said selector bar from its selected position.

40 5. In an adding machine, a selector bar, a numeral bar pivotally secured to said selector bar, means for recording any selected number of said numeral bar, said means adapted to simultaneously record the selected number of said numeral bar and cause said bars to be returned to their normal positions.

6. In an adding machine a recording member, a series of sliding selector bars, stops carried by said bars, an engaging member carried by said recording member adapted to engage said stops on said selector bars and hold said bars in their selected position.

55 7. In an adding machine, a recording member, a series of sliding selector bars, an engaging member carried by said recording member adapted to hold said selector bars in their selected position, said recording member, when operated, adapted to record the selected numbers carried by said selector bars.

8. In an adding machine, a recording member, a series of sliding selector bars, an engaging member carried by said recording

member adapted to hold said selector bars in their selected position, said recording member, when operated, adapted to record the selected numbers carried by said selector bars, and to allow said selector bars to be returned to their normal position after their selected numbers have been recorded.

9. In an adding machine, a series of selector bars therefor, a series of selecting members carried by each of said selector bars, a numeral bar carried by said selector bar, said selector bars being slidably mounted and adapted to be moved to different extents independently of each other in accordance with the number selected on each selector bar, the selected number on each bar after being moved to its limit of travel adapted to be arranged in a row with other selected and moved numbers of other selector bars, and a recording member to be operated upon and move said numeral bars downwardly.

10. In an adding machine, a series of selector bars therefor, a series of selecting members carried by each of said selector bars, said selector bars being slidably mounted and adapted to be moved to different extents independently of each other in accordance with the number selected on each selector bar, the selected number on each bar, after being moved to its limit of travel, adapted to be arranged in a row with other selected and moved numbers of other selector bars, and a recording member adapted to move a portion of said selector bars downwardly.

11. In an adding machine, a slidably mounted selector bar, said selector bar adapted to be operated to different extents, said selector bar having a numeral bar pivotally secured thereto, means for holding said selector bar in a selected position, and means for simultaneously recording a numeral on said numeral bar and releasing said selector bar whereby said selector bar can be returned to its normal position.

12. In an adding machine, a slidably mounted selector bar, a numeral bar pivotally mounted at one end to said selector bar, the opposite end of said numeral bar being resiliently secured to said selector bar.

13. In an adding machine, a slidably mounted selector bar, a numeral bar pivotally mounted at one end to said selector bar, the opposite end of said numeral bar being resiliently secured to said selector bar, and means for swinging said numeral bar downwardly from said selector bar.

14. In an adding machine, a slidably mounted selector bar, a numeral bar pivotally mounted to said selector bar, and a recording member adapted to depress said numeral bar.

15. In an adding machine, a slidably mounted selector bar, said bar adapted to be operated to different extents, a numeral car-

rying bar swingingly connected to said selector bar, a recording bar for holding said bars in any selected position, said recording member adapted to depress said numeral bar.

5 16. In an adding machine, a slidingly mounted selector bar, said bar adapted to be operated to different extents, a numeral carrying bar swingingly connected to said selector bar, a recording bar for holding said bars in any selected position, said recording member adapted to depress said numeral bar, and a totalizer wheel operated by said selector bar.

10 17. In an adding machine, a slidingly mounted selector bar, a numeral bar pivotally mounted to said selector bar, a recording member adapted to depress said numeral bar, and a totalizer wheel operated by said selector bar.

15 18. In an adding machine, a slidingly mounted selector bar, a numeral bar mounted to said selector bar, engaging portions formed on said numeral bar, and a recording member adapted to engage said engaging portions and hold said bars in their selected positions, said recording member when depressed causing said numeral bar to be moved downwardly from said selector bar.

20 19. In an adding machine, a slidingly mounted selector bar, a numeral bar mounted to said selector bar, engaging portions formed on said numeral bar, and a recording member adapted to engage said engaging

25 portions and hold said bars in their selected positions, said recording member when depressed causing said numeral bar to be moved downwardly from said selector bar, and means for disengaging said engaging portions from said recording member.

30 20. In an adding machine, a slidingly mounted selector bar, a totalizer wheel operated by said selector bar, a numeral bar mounted to said selector bar, engaging portions formed on said numeral bar, and a recording member adapted to engage said engaging portions and hold said bars in their selected positions, said recording member when depressed causing said numeral bar to be moved downwardly from said selector bar.

35 21. In an adding machine, a slidingly mounted selector bar, a numeral bar pivotally mounted to said selector bar, said numeral bar adapted to be moved parallel with said selector bar, and an inking roller for engagement with said numeral bar.

40 22. In an adding machine, a slidingly mounted selector bar, a numeral bar pivotally mounted to said selector bar, a recording member adapted to depress said numeral bar, and an inking roller for engagement with said numeral bar.

FERDINAND J. TILLMAN.
